RICHARD T. LANG, OF HEIDENHEIM-ON-THE-BRENZ, GERMANY, ASSIGNOR TO AMERICAN VOITH CONTACT COMPANY, INC., OF NEW YORK, N. Y., A CORPORATION OF NEW YORK

SCREW PRESS FOR DEWATERING AND WASHING DILUTED SUBSTANCES

Original application filed February 15, 1928, Serial No. 254,370. Divided and this application filed February 27, 1929. Serial No. 342,993.

This invention relates to screw presses for dewatering diluted substances; as for instance pulp in paper mills, oil seeds, bagasse, moist grain or the like. It has for its object to improve the construction and operation of screw presses so as to obtain highest consistency and uniform dryness of the whole substance when it leaves the press.

This application is a division of my earlier application, Serial No. 254,370, for patent on screw presses for dewatering and washing diluted substances, filed February 15, 1928.

With screw presses of the ordinary type the substance to be pressed out contains more liquor near the inner circumference of the threads of the screw than near the outer circumference of the threads, where the liquor contents are materially less. This condition is a very serious defect in this type of machine, because it does not permit economical operation. For obtaining a certain average density of pulp, it is therefore necessary to produce near the bottom of the screw threads a much higher consistency than required, in order to compensate for the condition of the pulp near the outer edges of the threads. A screw press having this disadvantage cannot be operated safely for pressing out at high density, because of its tendency to clog up on account of the relatively great consistency of the substance required near the bottom of the threads.

It has been proposed to overcome this drawback by providing perforations in the screw press body, inserting stationary or rotating perforated tubes into the press chamber, using perforated outlet plugs, etc. Such expedients, however, are objectionable. First a stationary tube as a continuation of the screw proper requires packing means within the press chamber, which is neither accessible nor easily controlled, and therefore are liable to give constant troubles, suffer with undue wear and necessitate a complicated design. Further, a rotating tube which can be fastened to the screw body, is operative only for relatively low densities and substances giving up the liquor contained therein easily. If "slow" wood pulp or the like has to be pressed out, however, to a density of more than 25%,

the pulp starts to rotate with the tube. This rotation acts back upon the pulp within the reach of the threads of the screw, so that such pulp will rotate also, thus producing a churning of the pulp instead of discharging it from the press.

An object of this invention is to avoid the complicated and unsatisfactory design comprising the stationary tube and to allow the employment of the rotating tube without incurring its disadvantages. For this purpose I provide obstructing means at the discharge end of the rotating tube to prevent the pulp from turning around with the tube, and at the same time I divide the pulp into separate streams before it leaves the outlet of the screw press. I further provide a plugging device at the outlet of the press for the purpose of controlling the density of the discharge pulp; and in connection with the plugging device in its immediate vicinity I utilize rotating cutting means which disintegrate the pulp after it has passed the obstructing means and break it up into small particles, which leave the outlet spout of the press freely. This disintegration of the highly dry pulp at the discharge end is necessary because a coherent mass would accumulate at the supporting means for the plugging device and produce an uncontrollable back pressure upon the pulp to be discharged, with the result of clogging the machine up in a very short time.

The drawings show an embodiment of my invention.

Figure 1 presents a vertical longitudinal section through the outlet end of a screw press according to my invention, showing the improved arrangement of the press chamber with the obstructing and cutting means and the plugging device; and

Figure 2 is a top plan of same.

The same numerals identify the same parts throughout.

Numeral 1 indicates a screw in a perforated shell 2, imbedded in the outer casing 3, to which the outlet 4 is attached. Fastened to the frame or body of the device adjacent the outlet 4 are two rods 5 which carry a member 6 with the bearing 7 supporting the end of the shaft 8 of the screw 1. The screw

1 is hollow and has no threads on the discharge end; but is there formed as a cylinder made of one or more curved perforated plates 9 fastened in place thereon. This threadless continuation or extension of the screw body 5 forms with the enveloping outer perforated shell 2 a press chamber through which the pulp passes under controllable pressure after it has left the threads of the screw. Within the shell 2 adjacent the outlet 4 one or 10 more knife-like obstructions 10 are fastened to prevent the pulp from turning around with the perforated plates 9 on the screw body in the press chamber. In practice these 15 parts 10 do not materially retard the forward motion of the pulp.

Movable with the screw body near the outlet 4 are cutting blades 11 which break the mass of pulp passing through the press 20 chamber into small particles, thereby allowing a free discharge of these particles at the outlet. These blades are mounted on the throttling or discharge plug 12, which can be moved towards or away from the outlet carrying the stationary obstructing means 10, thereby changing the clearance between the parts 10 and 11. The plug can slide on the screw 25 1 by reason of the feather key 13 on the screw engaging a keyway in the plug 12; and partakes of the rotation of the screw. Forward and backward motion can be imparted to the plug 12 by means of the slip collar 14, rotatably mounted between flanges on the end of the plug 12, and movable by arms 15 and 30 a lever 16 mounted on a spindle 17 in bearings 18. The parts 15 and 16 are rigid with each other, and the sleeves 18 are fastened to the rods 5. Weights 19 are carried on the levers 16. At 20 is a threaded rod which 35 passes through a threaded bar 21, pivotally attached to the levers 16. The rod 20, to which a hand wheel 22 is affixed, rests in a cavity or bearing 23 on the bearing 7. With the rod 20 and wheel 22 one can set and lock 40 the plug 12 at a desired distance from the outlet 4.

I have shown herein one embodiment of my invention and have in connection therewith described certain operative details of construction, but I do not desire to be limited thereto. For example, it is not necessary that the threadless end of the screw with the 45 perforated plates fastened thereon be in one piece with the screw, but it can as well be a separate section secured to the screw.

I claim:

1. In a screw press, having a casing and a rotary screw forming an annular outlet space at the outlet end of the casing and the screw 50 having a threadless part extending well beyond said outlet end, the improvement consisting of a frame at the free end of the threadless part, provided with a bearing receiving the axis end of the threadless part, a rod means extending from the casing, an an-

nular plug feathered on the threadless part, to be rotated with the screw and to have independent movement axially of the threadless part toward and away from the outlet space, and operative leverage means slidable at 70 their pivotal portion on the rods of the frame acting on the plug for normally urging movement of the plug toward the outlet space, including a substantially horizontally positioned weighted arm as the motivating agent, whereby the raising or lowering of said weighted arm will axially move said plug away from or toward said outlet. 75

2. In a screw press, the combination with a casing and a rotary screw having an annular outlet space at the outlet end of the casing and the screw having a threadless part extending beyond said outlet end, of a frame supported by the casing and carrying a bearing receiving the axial end of the threadless part, an annular plug rotatable with the screw and slidable axially of the threadless part for controlling the discharge of material through the outlet space, operative means on the frame for normally urging movement of the plug toward the outlet space, including a substantially horizontally projecting weighted arm as the motivating agent, and means for supporting the weighted arm at an elevation including a hand operated vertically positioned adjusting screw the lower end of which is loosely seated in a socket in the frame so that as the weighted arm is raised the screw will accompany it. 90

3. In combination with a screw press having a casing and a rotatable screw therein forming an annular outlet space at the outlet end of the casing and the screw having a threadless part extending beyond said outlet end, an annular plug for the outlet space, feathered on the threadless part to rotate therewith and to move axially thereon to and from the outlet space for controlling the discharge of material therethrough, means for controlling the axial movement 110 of said plug, comprising a bell crank device mounted for rocking movement with one arm connected by a slip collar to the plug and the other arm extending substantially horizontally and weighted to normally swing the device in a direction to move the plug toward the outlet space, and adjustable means for supporting the weighted arm at an elevation. 115

4. In a screw press having a casing and a screw therein forming an annular outlet space at the outlet end of the casing, the screw having a threadless part extending beyond said outlet end, and an annular plug slidable axially on the threadless part for controlling the discharge of material through the outlet space and feathered onto said threadless part, the improvement for axially reciprocating the plug comprising a slip collar on said plug, a rocking arm pivotally and 120

slidably supported by said casing and in connection with said collar, and means for sliding said rocking arm whereby to cause movement of the plug to close or open the 5 annular outlet space.

5. In a screw press having a casing with an outlet end and a screw with a threadless part extending outwardly through the outlet end of the casing and forming an annular outlet space therewith, an annular plug mounted on the threadless part for axial movement thereon and away from the outlet space, the improvement consisting of rods 10 extending from the casing, connected bell crank devices pivotally mounted on said rods and slideable thereon, said devices having one arm weighted and substantially horizontal, while the other arm is in connection with a slip collar on said plug, a bearing in engagement with said rods, a shaft in connection 15 with said weighted arms, and means for raising and lowering said weighted arms whereby axially to move said plug backward or forward.
- 20 25 In testimony that I claim the foregoing as my invention, I have signed my name hereto.
